UNITED STATES PATENT OFFICE.

GEORGE HILLARD BENJAMIN, OF NEW YORK, N. Y.

TUNNEL KILN.

Application filed February 8, 1922. Serial No. 534,839.

To all whom it may concern:

Be it known that I, GEORGE HILLARD BENJAMIN, a citizen of the United States of America, residing at New York, county of 5 New York, State of New York, have invented a certain new and useful Improvement in Tunnel Kilns, of which the following is a specification.

My invention relates to improvements in 10 tunnel kilns of which the following is a specification.

Tunnel kilns have heretofore been heated directly, by the combustion of coal, or indirectly by the combustion of gas and air, 15 or oil and air. Both methods have been open to objections; the principal one of which is, however, that it is found difficult to control the heat, i. e., to meet the requirements for variation of heat along the length 20 of the kiln. When the heat cannot be regulated, the result, for instance in treating pottery, is the production of a large number of seconds. This is most objectionable and expensive.

25 To overcome the objection of the lack of heat regulation, I have devised the construction described in this specification, in which the heating, as well as the regulation of the heat, is effected through the application of electrically developed heat in one portion of the length of the kiln, or alternatively, by the combined effect of heat developed through the combustion of gas and air in one portion of the length of the kiln, and 35 heat developed by electricity in another portion of the kiln.

In the accompanying drawings, I have shown my invention applied to kilns of the open as also of the muffle type. I have also 40 shown various features of construction which are applicable not only to kilns containing my present improvements in heating, but to kilns heated by the older methods as above set forth; all of which improvements will be specifically pointed out in the 45 specification.

The accompanying drawings, which are largely diagrammatic, will serve to illustrate my invention, in which,

50 Fig. 1 is a longitudinal vertical section, with certain of the parts in elevation.

Fig. 2 is a horizontal section taken along the line II—II of Fig. 1.

55 Fig. 3 is a transverse section taken along the line of III—III of Fig. 1.

Fig. 4 is a horizontal section showing a modification of the construction shown in Fig. 1, this figure showing two heating zones instead of one as illustrated in Fig. 1.

Fig. 5 is a vertical section taken along 60 the line of V—V of Fig. 4.

Fig. 6 is a vertical section taken along the line of VI—VI of Fig. 4.

Fig. 7 is a longitudinal vertical section corresponding to Fig. 1, which shows a construction differing from Fig. 1, in that the means for distributing the heat is located below the kiln structure, whereas in Fig. 1, it is above the kiln structure.

Fig. 8 is a vertical transverse section along 70 the line of VIII—VIII of Fig. 7.

Fig. 9 is a diagram of the circuit connections.

In the drawings, 5 represents the kiln structure which may be of any suitable 75 construction. The kiln structure in Figs. 1 and 7 is divided into three zones in the direction of the length of the kiln, A, B and C; A being the preliminary heating zone, B the zone of high temperature, and 80 C the cooling zone.

In Fig. 4, the two heating zones A and B are shown, and it is assumed that a cooling zone C, not shown in this figure, will be added to the right of the zone B in the actual 85 kiln.

The interior of the kiln forms the main or treating chamber 6, and is provided with tracks 7, over which are adapted to be moved, cars 8, which carry the goods to be treated. 90 At the ends of the kiln are doors 9, which can be lifted and lowered as required to allow entrance of the cars into, and exit from, the kiln. Situated on each side of the kiln in the zone B, Figs. 1 and 7, and zones A and B, Fig. 4, are pairs of heating chambers 10. These chambers are structurally independent of the walls of the kiln and of each other.

In Figs. 1, 2 and 3 the heating chambers 100 are formed with a single continuous wall 11, with openings 12 at the top; whereas, in Figs. 4, 5 and 6 the heating chambers are formed with double walls, 11 and 13, with openings 12 at the top; openings 14 at the 105 bottom, and openings 15 at the top of the wall 13; the arrangement of 4, 5 and 6 being such as to leave a space 16, between the walls 11 and 13.

Situated in the bottom of the heating 110

chambers are two blocks 17 and 18, such as a refractory carbon. Located between these blocks is a third block 19, of high resistance material. The blocks 17 and 18 are given such shape as to support the block 19 above the bottom of the heating chambers. Arranged over and covering the blocks 17 and 18 and 19 is a body of high resistance material 20, preferably lump carbon. Located in the openings 12 of the chamber are carbon electrodes 21 connected to any suitable source of electricity through conductors 22. In Figs. 3, 5 and 6 the electrodes are surrounded with sleeves 23.

In Figs. 1, 2 and 3, the gases developed by the combustion in the heating chambers can flow through the openings 12 into the cavity of the heating chamber 6.

In the construction shown in Figs. 4, 5 and 6, by means of the sleeves, the gases are discharged out of the kiln. By reason of this condition, the construction shown in Figs. 1, 2 and 3 may be termed an open kiln, whereas that shown in Figs. 4, 5 and 6, a muffle kiln.

The electrodes, as will be seen by the diagram, Fig. 9, are arranged in multiple, and the heating is due to the resistance of the refractory material 20 between the electrodes, and the regulation of the current can be effected by the rheostat 25.

It will be obvious that the temperature of the zone B may be regulated, not only by the amount of current fed to each pair of electrodes, but by putting into operation one or both pairs of electrodes. The temperature can be determined by thermometer 26, introduced into the top of the kiln over the heating chambers.

In the operation of the kiln, the refractory resistance material 20 is gradually destroyed and it is necessary to remove and replace it. Provision is made for removing refractory resistance material through the doors 27, at one end of each of the heating chambers.

Referring again to Fig. 1, means is disclosed for conveying the surplus heat from the cooling zone C into the preliminary heating zone A, which means consists of a picking-up chamber 28. Located over the top of the kiln, is a flue 29 and pump 30, and a flue 31 from pump 30 leading into the forward end of the preliminary chamber A.

In Fig. 7, the picking-up chamber consists of a series of openings 32 in the bottom of the side walls of the kiln, which lead through flue 33 to pump 34, thence through flue 35 to a series of openings 36 in the bottom of the side walls of the preliminary heating chamber.

In this figure, a second series of openings 37 in the bottom of the side walls of the preliminary heating chamber A, communi-

cate through flue 38 with the pump 39, adapted to discharge through the flue 40 to the atmosphere.

In the upper portion of the side walls in the construction is an opening 41 connected with the flue 42 through which the heat in the cooling chamber C, may be withdrawn and a similar opening 43 is shown in the top of the side wall of the preliminary chamber. In Fig. 4, the preliminary heating chamber is provided with heating chambers, fired by the combustion of gas and air introduced by the burners 44. The products of combustion are carried away by stacks 45.

The operation of my improved kiln is as follows:

The door 9 at the left hand end of the kiln is raised, and a car carrying the material to be treated is introduced into the kiln. The car remains in the chamber A for a sufficient time to thoroughly heat the material carried on the car, after which the door 9 is again opened and a second car introduced. As successive cars are introduced, the first car passes into the zone B, where it is subjected to the highest temperature and maintained at such temperature during the time the car is in zone B and is gradually cooled as the car approaches the right hand end of the kiln.

The heat carried by the material passes upward into the picking-up space 28, and the picking-up flue 29, and is delivered into the zone A; thus conserving the heat. By the pump 39, Fig. 7, the heat in zone A can be regulated. Any surplus heat in A or C may be withdrawn through flues 41 and 43.

So far as relates to the construction shown in Fig. 4, it is practically the same as that shown in the other figures, with the exception that means are provided for heating the zone A by heat derived by the combustion of gas and air. This seems desirable in treating materials which require a high temperature at the time they are introduced into the kiln, and a higher temperature during the time the goods are passing through zone B.

It will be understood that in the construction shown in Fig. 4, the features of the construction shown in Fig. 1 and Fig. 7 for controlling heat from zone C and delivering it into zone A, can also be employed.

In this specification, I have described the heating means of zone B as effected by the passing of electric current between the electrodes, with an interposed resistance in the nature of a refractory material. Manifestly, other means of generating electric heat may be employed. I am aware that it has heretofore been proposed to heat kilns by heat developed by electricity, and such I do not broadly claim; my invention being limited to the application of electric heat when.

used in connection with heating chambers, disposed as, and having the general construction illustrated in the drawings.

By reason of my improved construction, 5 the heat can not only be regulated within practical limits, but by reason of the air circulation, surrounding the heating chambers, effective distribution of the heat is obtained, and all danger of over-heating of 10 materials under treatment, at the sides of the cars, and where exposed to the highly heated heating chambers, is avoided.

It will be understood that owing to the 15 construction of the heating chambers, and their relation to the walls of the kiln, there is a constant circulation of heated air from the bottom of the kiln, upward, around the heating chambers, to the top of the kiln, and then downward, through the material on the 20 carriages; this circulation being continuous and automatic.

Having thus described my invention, I claim:—

1. A tunnel oven comprising a main 25 chamber through which goods to be heated can be caused to travel; a heating chamber on each side of the main chamber, structurally independent of the side walls and roof of the chamber; and means in each chamber 30 for converting and transmitting electric current into heat.

2. A tunnel oven comprising a main chamber; a heating chamber located on each side of the main chamber, but structurally independent therefrom; a body of high electrical resistance in each heating chamber; and spaced electrodes in each of said chambers in contact with the material of high electrical resistance.

3. A tunnel oven comprising a main chamber; a heating chamber located on each side of the main chamber, but structurally independent therefrom; a body of material of high electrical resistance, situated in each chamber; spaced pairs of electrodes in each chamber in contact with the material of high electrical resistance; a sleeve surrounding each electrode external to the heating chamber, communicating at one end 50 with the heating chambers, and at the other end with the exterior of the kiln, whereby the gaseous bodies generated in the heating chambers will be conducted from the heating chambers to the exterior of the kiln.

4. A tunnel oven comprising a main

chamber; a heating chamber located on each side of the main chamber; a cleaning door at one end of each of the heating chambers; together with means for generating electric heat in the interior of the heating chambers. 60

5. A tunnel oven comprising a main chamber; and divided longitudinally into three zones; a preliminary heating zone, a high temperature zone, and a cooling zone, a heating chamber located in the zone of high 65 temperature; together with means for setting free heat due to the passage of electric current from the resistance medium within the heating chamber, whereby the heat in the body of the kiln will be that radiated 70 from the heating chamber.

6. A tunnel oven comprising a main chamber; and divided longitudinally into three zones; a preliminary heating zone, a high temperature zone, and a cooling zone; 75 a heating chamber located in the zone of high temperature; together with means for setting free heat within the chamber by the passage of an electric current through a high resistance medium, and means for conveying 80 the excess of heat from the cooling zone, and delivering it into the preliminary heating zone.

7. A tunnel oven comprising a main chamber; a heating chamber; said heating 85 chamber formed with continuous walls perforated at the top at two points; said chamber located at a distance from the bottom, side and top walls of the kiln, whereby air may be circulated around the chamber; a body of material of high electrical resistance situated in the heating chamber; and a pair of electrodes, having their lower terminal ends in the chamber, and in contact with the material of high electrical resistance; and their upper terminals ends connected in multiple to a source of electric energy. 95

8. The herein described method of heating the treating chamber of a continuous kiln; 100 which consists in developing electrical heat within a chamber situated within the treating chamber, but structurally independent therefrom.

In testimony whereof, I affix my signature, 105 in the presence of two witnesses.

GEORGE HILLARD BENJAMIN.
